EDGAR E. BROSIUS, OF PITTSBURGH, PENNSYLVANIA

TUYÈRE STRUCTURE AND METHOD OF CHANGING THE SAME

Application filed June 30, 1931. Serial No. 547,847.

The present invention relates broadly to furnaces of the type usually referred to as blast furnaces, and more particularly to an improved tuyère structure for use with such furnaces, affording novel means for changing the tuyère with the furnace operating under full pressure.

It is customary in the art to which the present invention relates to provide blast furnaces with tuyères, usually from ten to sixteen individual tuyères being utilized in each furnace, these being distributed symmetrically about the upper circumference of the hearth just below the bosh. Such tuyères function to provide blast admitting means to the furnace, and for determining the height to which the slag may rise in the furnace. Ordinarily such tuyères are made of copper, and water cooled to maintain as long a period of usefulness as possible. Due to the intense heat to which they are subjected however, the tuyères burn away more or less rapidly, thus requiring rather frequent renewal.

While the actual operation of blast furnaces varies to some extent in accordance with the ideas of the particular operators in charge thereof, it is not infrequent to operate furnaces of this character under a wind pressure of from 10 to 30 lbs. When it is necessary, with standard installations, to replace a tuyère, the blast has to be cut off from the furnace, the tuyère removed, a new tuyère inserted and the blast again turned on. The actual time period for changing a tuyère is usually in the neighborhood of from ten to fifteen minutes, an additional time period being required for the re-establishing of the desired operating conditions within the furnace after the blast is resumed. Assuming an elapsed time of twenty minutes, with a large furnace, the production of the furnace has been decreased in the neighborhood of from ten to twenty tons, furnaces of the character under consideration being adaptable for production at substantially the rate of from one half to one ton per minute.

From the foregoing, it will be apparent to those skilled in the art that any construction capable of expediting the tuyère changing

operation, is highly desirable from the standpoint of continuity of furnace operation and production obtained, as well as from the standpoint of safety to the operators during the tuyère changing operation. 55

The present invention has for one of its objects the provision of an improved tuyère structure such that it may be changed with the furnace operating under full wind pressure. 60

In the accompanying drawings I have illustrated more or less diagrammatically, a preferred embodiment of the present invention. In the drawings:

Figure 1 is a view largely in vertical section through a portion of a blast furnace illustrating my improved tuyère structure in operative relation thereto; 65

Figure 2 is a transverse sectional view on the line II—II of Figure 1, looking in the direction of the arrows;

Figure 3 is a transverse sectional view on the line III—III of Figure 1;

Figure 4 is a view similar to Figure 1, illustrating a slightly modified embodiment 75 of the invention;

Figure 5 is an end elevational view of a portion of the structure illustrated in Figure 4;

Figure 6 is a transverse sectional view on the line VI—VI of Figure 4; 80

Figure 6' is a detail sectional view of one of the water connections;

Figure 6'' is a transverse sectional view on the line VI—VI of Figure 6'; 85

Figure 7 is a detail longitudinal view through a portion of the structure illustrated in Figure 4 showing certain of the parts in different position;

Figure 8 is a view similar to Figures 1 and 4, showing still another embodiment of the invention; 90

Figure 9 is a detail plan view of the blow pipe and valve structure of Figure 8;

Figure 10 is a detail sectional view on the line X—X of Figure 8; and 95

Figure 11 is an end elevational view of the construction illustrated in Figure 8.

Having reference more particularly to the drawings, there is illustrated a portion of the 100

hearth wall 2 of a usual blast furnace having in position therein a tuyère cooler 3. Projecting inwardly from the tuyère cooler, and supported at least partly in position 5 therein is a tuyère 4, which tuyère may be of any standard construction. Extending rearwardly from the tuyère is a blow pipe 5 provided intermediate its ends with a valve 5' of suitable type adapted when closed to 10 vide the blow pipe into an inner section A and an outer section B.

Normally positioned in the inner section A of the blow pipe is a tuyère support or distance piece 6 of such overall dimensions 15 with respect to the blow pipe as to permit the same to be axially moved therethrough. The distance piece 6 is formed with an upwardly and outwardly curved wall 7 constituting a continuation of the blast opening 8 20 communicating with the tuyère, and constituting the back wall of an opening 9 in one side of the distance piece. The opening 9 communicates with a leg pipe 10 constituting a lateral extension from the blow pipe and 25 communicating through a suitable goose-neck 11 with a bustle pipe 12.

Extending longitudinally through the distance piece 6, and preferably through channels 14 in the diametrically opposite walls 30 thereof are water cooling pipes 15 operatively connected at their forward ends to the tuyère 4 for delivering cooling water thereto and removing the water therefrom. The water cooling pipes 15 are herein illustrated 35 as formed with a tapered nose 16 fitting into a correspondingly shaped socket in the tuyère, thus permitting the pipes and tuyère to be readily disconnected, although it will be apparent that the pipes may be threaded or otherwise secured to the tuyères if desired.

In actual operation, the hot blast, under suitable pressure, is delivered from the bustle pipe 12 through the goose-neck 11 to the distance piece 6 and thence into the tuyère. So 45 long as the tuyère remains in proper operative condition, the blast may be continued. In accordance with the present invention, when the tuyère becomes burned away to such an extent that replacement is required, the 50 water pipes 15 and the distance piece 6 are moved axially of the blow pipe out of the inner section A and into the section B. This movement is accomplished without cutting off the wind from the furnace. As soon as 55 the distance piece is in position within the section B, the valve 5' is moved across the blow pipe, thus cutting off communication between the two sections. At this time the blast continues to pass from the bustle pipe 60 to the tuyère, whereby normal operation of the furnace is continued. The closure 17 is then opened, and the distance piece removed from the blow pipe. A new tuyère is thereupon attached to the end of the distance piece 65 in the desired cooperative relation to the cool-

ing pipes 15, and the distance piece and tuyère inserted in the section B. During this insertion of the new tuyère, and distance piece, the supply of cooling water for the tuyère is turned on, so that the tuyère is being cooled during its insertion into position within the furnace. The closure 17 is then re-applied, the valve 5' opened, and the distance piece and tuyère shoved forwardly into the position shown in Figure 1. This forward movement causes the old tuyère to be pushed into the furnace.

In cases where it is desired to remove the old tuyère, this may be accomplished either by suitably securing it to the distance piece 80 or to the cooling pipes whereby it is withdrawn concomitantly with the withdrawal of the distance piece. In either case, however, the substitution of tuyères is made possible, while retaining full wind pressure on the 85 furnace.

To those skilled in the art, it will be apparent that permitting the old tuyère to remain in position possesses certain advantages, particularly with respect to protecting the seat 90 against either burning out or the accumulation of any matter thereon. By thus protecting the seat, the insertion of the new tuyère is facilitated.

By reference more particularly to Figure 1 of the drawings, it will be noted that the tuyère is of substantially truly cylindrical outer contour, thus providing a straight seat where it engages the cooler 3. This permits the old tuyère to be pushed into the 100 furnace when the new tuyère is moved into position, and materially simplifies the construction of the tuyères themselves. The use of such a straight seat on a tuyère of the character described constitutes one advantageous 105 feature of the construction.

The present invention further obviates the necessity of packing clay in around the nose of an old tuyère, as customary in the art, to protect the same, and the operators, during 110 the tuyère changing operation, and consequently obviates the subsequent step of prickling the clay to re-establish a blast communication with the interior of the furnace. It likewise obviates the present difficulty with respect to the lodging of pulverulent material 115 in the furnace end of the blow pipe when the wind pressure is cut off, inasmuch as with the present construction, the continuance of the pressure tends to preclude any tendency 120 of the blow pipe to collect material from the furnace. Thus, the free movement of the distance piece into position with its new tuyère, is made possible.

In the accompanying drawings I have not shown the water supply connections for the pipes 15. It will be understood, however, that water will preferably be supplied thereto through flexible connections 18 of such nature that the desired movement of the cool- 125

ing pipes is made possible in order to permit insertion and removal of the distance piece.

Reference has hereinbefore been made to the use of a distance piece, this being referred to as the tuyère support. It will be understood, however, that the term "tuyère support" as utilized particularly in the claims, is a generic expression and finds response equally in the pipes 15 and in the distance piece. The tuyère support might equally well comprise any other structure or means effective for holding it in the desired position during insertion or removal or while in position within the furnace. The expression therefore is not one of limitation but merely one of definition of function unless otherwise restricted by structural limitations.

In certain cases it is desirable to provide for the complete elimination of the blow pipe during the normal operation of the furnace. In Figures 4 to 7, both inclusive, there is provided a structure by means of which removal of the blow pipe is made possible as soon as a new tuyère is in position. In the embodiment illustrated in these figures, there is provided a tuyère cooler 20 having a straight seat 21 for a tuyère 22, the tuyère and cooler being of the general construction before described. Cooperating with the tuyère is a distance piece 23 having a side opening 24 through which the blast may pass from the bustle pipe to the tuyère through a suitable goose-neck 25. The goose-neck is herein illustrated as including a universal joint connection 26 with an outlet 27 on the bustle pipe and with a similar joint 28 between the goose-neck and the leg pipe 29. The goose-neck is further illustrated as being resiliently coupled to the leg pipe by means of a spring joint 30 effective for constantly maintaining the desired seal between the respective parts. The inner section A' of the blow pipe is herein illustrated as being formed integrally with the leg pipe 29, and as having a flange 31 formed on the outer end thereof. The end 32 of the inner section is preferably machined to provide a seat for a slide 33 having a function corresponding to that of the valve 5'.

The outer section B' is generally similar to that illustrated in Figure 1, but is herein illustrated as provided with ears 34 adapted to overlap lugs 35 formed on a seat flange 36. The seat flange is of such construction as to provide the opposite seat for the slide 33, the said flange and inner section A' being held in yieldingly assembled relationship by springs 37 which exert sufficient pressure on the slide to maintain the desired seal between the parts while permitting sliding movement thereof. The seat flange 36 is further shown as being yieldingly held in position by a spring 38 surrounding a link 39 having a pivotal mounting 40 on a suitable bracket 41 secured to the furnace wall.

The distance piece 23 is shown as having

channels 42 formed therein, corresponding to the channels 14, and adapted to receive cooling pipes 43. As will be apparent more particularly from Figure 6', the distance piece is provided with couplings having threaded inlet openings 44 adapted to receive the cooling pipes 43. These couplings are likewise formed with bosses 45 providing threaded inlets 46 with which cooling pipes 47 may be connected. The openings 44 and 46 have 75 their axes disposed at substantially right angles to each other, the openings 44 being adapted to receive cooling pipes which will extend longitudinally through the outer blow pipe section B', as illustrated for example 80 also in Figure 1, while the openings 46 receive cooling pipes which extend laterally from the inner section A'. The distance piece is conveniently provided with valves 48 of any suitable construction adapted to seal either the openings 44 or the openings 46.

As illustrated in Figures 6' and 6'', the valve comprises a ball guided by a suitable rib or track 49. With this construction, when the axially extending pipes 43 are utilized, the ball valves 48 will be in the full line position illustrated in Figure 6', thus sealing the openings 46. When, however, the pipes 47 are utilized, the ball valves will move to their dotted line position, thus sealing the openings 44. This construction permits the axially extending pipes 43 to be utilized for supplying cooling water to the tuyère during the insertion of the new tuyère. These pipes may then be removed and the 100 pipes 47 substituted for continuing the supply of cooling water. Preferably both sets of pipes will be in position before the supply of cooling water is cut off through the pipes 43. When the change is to be made, it is then merely necessary to stop the flow of water through the pipes 43 and initiate a water flow through the pipes 47, the valves 48 moving as described to seal the openings 44. Thereafter the pipes 43 may be removed. 105 Thereupon, it is possible to remove the fastening pins by means of which the ears 34 are connected to the lugs 35, and thus remove the entire outer section B' of the blow pipe structure. Thereupon a peep hole closure 110 plate 50 may be applied to the outer end of the inner section A', as illustrated in Figure 7, thus permitting observation of the tuyère operation. The plate 50 carries a sleeve 50', the inner end of which may contact the outer end of the distance piece 23.

With the construction just described, when it is desired to effect removal of a tuyère, the valve is moved to closed position, the peep hole closure plate 50 removed, and the blow pipe section B' applied, the slide 33 then being moved to establish communication between the inner and outer sections of the blow pipe. Thereupon the pipes 47 are removed and the pipes 115 120 125 130

43 substituted. The distance piece may then be withdrawn from the inner section A' into the outer section, and the slide 33 moved to cut off communication between the sections. The operation then proceeds similarly to that before described. The new tuyère having been applied to the distance piece, it is moved forwardly by the pipes 43, the pipes 47, the slide 33 closed and the blow pipe section B' removed to permit application of the peep hole closure plate.

5 In Figures 8 to 11, both inclusive, there is illustrated a slightly different embodiment of the invention, in that the distance piece 23' is formed with lugs 51 adapted to receive therebehind a head 52 carried by a stem 53. This stem has a threaded outer end 54 cooperating with a puller gear 55 having a bearing 56 on the outer end of blow pipe section B''. When it is desired to effect substitution of tuyères, the general operation just described takes place. This puller gear is in turn operated through a gear train 57 which may be manually rotated at will by means of a hand wheel 58, the gear reduction being such that a new tuyère may be positively forced into position, or the parts withdrawn to permit a tuyère changing operation. The outer blow pipe section B'' having been applied, however, the gear 55 is rotated to effect axial movement of the distance piece 23', the cross-head 52 prior to this time having been turned into position to engage behind the lugs 51. The distance piece 23' having been moved outwardly to an extent sufficient to permit closing of the valve or slide 33', the blow pipe section B'' is swung to an open position, a new tuyère applied, and the operation reversed.

40 With all of the forms of the invention hereinbefore described, means is provided for supporting a tuyère during the operation of substituting the same for a tuyère which has previously burned out. In this manner, it is possible for the operator to be at a distance from the furnace such that he may expeditiously perform the necessary operations for effecting changing of a tuyère, while being assured that the new tuyère will be properly guided into position.

45 Certain advantages of the invention arise from the improved tuyère structure permitting a tuyère to be changed while maintaining full pressure on the furnace.

50 Other advantages arise from the improved method of changing tuyères, by means of which the production of the furnace and the maintenance of uniform or substantially uniform conditions therein during a tuyère changing operation, is made possible.

55 While I have herein illustrated and described certain preferred embodiments of my invention, it will be understood that changes in the method and structure herein disclosed

may be made without departing either from the spirit of my invention or the scope of my broader claims.

I claim:

1. In the method of changing tuyères, the steps comprising moving a tuyère support outwardly from a furnace while delivering a blast to the furnace, sealing the tuyère support from communication with the furnace, applying a new tuyère to the support, re-establishing communication between the tuyère support and the furnace, and moving the tuyère support and tuyère into position in the furnace. 70

2. In the method of changing tuyères of a furnace having a blow pipe, the steps comprising moving a tuyère support outwardly from the furnace to a position within a portion of the blow pipe, cutting off communication between the portion of the blow pipe containing the tuyère support and the furnace, removing the tuyère support from the blow pipe and securing a new tuyère thereto, inserting the tuyère support and tuyère within the blow pipe, re-establishing communication between the portion of the blow pipe containing the tuyère support and new tuyère and the furnace, and moving the new tuyère and tuyère support inwardly within the blow pipe to bring the new tuyère into operative position within the furnace. 80

3. In the method of changing tuyères of a furnace having a blow pipe, the steps comprising moving a tuyère support outwardly to a position within a portion of the blow pipe 100 while retaining the outer end of the blow pipe substantially sealed and while keeping a blast on the furnace, cutting off communication between the portion of the blow pipe containing the tuyère support and the interior of the furnace, opening the outer end of the blow pipe and removing the tuyère support therefrom, adding a new tuyère to the tuyère support, inserting the same within the blow pipe, closing the outer end of the blow pipe, re-establishing communication between the outer end of the blow pipe and the interior of the furnace, and advancing the tuyère support and new tuyère inwardly within the blow pipe to bring the new tuyère 110 into operative position within the furnace. 105

4. In a blast furnace, a blow pipe, means for substantially sealing the outer end of the blow pipe, sealing means carried by an intermediate portion of the blow pipe and a tuyère support movable axially of the blow pipe from a position inwardly of the intermediate sealing means to a position between the two sealing means. 120

5. In a tuyère structure, a blow pipe, a tuyère support therein, said tuyère support being movable axially of the blow pipe, and means for sealing off the tuyère support when so moved from communication with the furnace. 125

6. In a tuyère structure, a blow pipe having a blast connection therewith, a tuyère support having a side opening movable into communication with said blast connection, means for moving said tuyère support axially within the blow pipe while continuing a blast through said connection, and means for sealing off the tuyère support from communication with the interior of the furnace when so moved.

10 7. In a tuyère structure, a blow pipe comprising an inner and an outer section, means for delivering a blast to the inner section, means for cutting off communication between the inner and outer section and a tuyère support movable from the inner section to the outer section.

20 8. In a tuyère structure, a blow pipe comprising an inner and an outer section, means for delivering a blast to the inner section, and means for cutting off communication between the inner and outer section, there being a tuyère support within said blow pipe movable from one section thereof into the other.

25 9. The method of operating blast furnaces, comprising supplying a blast to the furnace through a tuyère and tuyère support, removing the tuyère support while continuing the blast, securing a new tuyère to the tuyère support, and establishing cooperative relation between the tuyère support and new tuyère and the furnace.

30 10. In the method of changing tuyères, the steps comprising continuing the delivery of a blast to the furnace through a tuyère opening, supporting a new tuyère at a point exteriorly of the furnace and then moving the new tuyère while so supported through said opening into position within the furnace.

40 11. In a tuyère structure, a sectional blow pipe comprising a pair of detachable sections, sealing means effective for cutting off communication between the sections, and a tuyère support movable from a position within one section to a position within the outer section.

45 12. In a blast furnace, a blow pipe comprising a detachable outer section, and means for substantially sealing the outer section of the blow pipe from the inner portion thereof.

50 50. In testimony whereof I have hereunto set my hand.

EDGAR E. BROSIUS.
